UNITED STATES PATENT OFFICE.

JENS ORTEN BOVING, OF LONDON, ENGLAND.

ELECTRIC FURNACE.

1,281,280.

Specification of Letters Patent. Patented Oct. 15, 1918.

Application filed September 4, 1917. Serial No. 189,567.

To all whom it may concern:

Be it known that I, JENS ORTEN BOVING, subject of the King of Great Britain, residing at Imperial Buildings, No. 56 Kingsway, London W. C. 2, England, have invented new and useful Improvements Relating to Electric Furnaces, of which the following is a specification.

This invention relates to means for utilizing the combined effects of hydraulic and electric power to regulate automatically the supply of electricity to an electric furnace.

The regulation is derived by adjusting the position of the carbon electrode in relation to the molten metal which is being operated on within the furnace, the displacement of the electrode for the purpose being effected by the force of fluid-pressure, on hydraulic operating organs and an electro-magnetic organ provided to command the valvular elements whereby the supply of pressure-fluid to the said hydraulic operating organs is so automatically adjusted as to approximate closely to the maintenance of a constant current of electricity through the furnace.

The said electro-magnetic organ is energized by the agency of the electric current which is supplied for the operation of the furnace, a shunt being taken from the main lead for the purpose.

Alternatively the electro-magnetic organ may be energized by a secondary current derived by a transformer from the main electric current acting as a primary.

Further, alternatively to employing an electro-magnet and a longitudinally displaced armature thereof as the electro-magnetic adjusting organ I may employ a construction such as is used in a single phase repulsion motor.

By such means I am able to provide a powerful force organ to suitably constrain and displace the carbon electrode which organ is very responsive to fluctuations of the electric current in a manner to cause the fluctuations to be subdued to a very efficient degree, the electro-magnetic adjusting organ being required to perform merely the duty of regulating the leakage of a small portion of the pressure-fluid past a balanced escape valve thus encountering only a minute resistance to its displacement.

The accompanying drawings show, as a representative example, a form of construction of apparatus possessing the above de-

scribed features some of the parts therein represented being alternative.

In these drawings:

Figure 1 is a sectional elevation of the apparatus,

Fig. 2 is a sectional elevation, on a larger scale, showing the valvular elements employed in maintaining in action the fluid-pressure operating organs and showing also one construction of electro-magnetic adjusting device, and:

Fig. 3 shows a construction a portion of which is alternative to that shown in Fig. 2.

Referring to Fig. 1, A is the furnace body, B the metal undergoing treatment and C is the carbon electrode. The electrode is carried by an arm D so constructed and provided with rollers d d as to be adapted to be vertically displaced with facility along the mast F. The force necessary to readily effect the displacement is provided by means of the fixed hydraulic cylinder G and the sliding ram H through the bore of which liquid under pressure is admitted to the cylinder G from a flexible pipe I in a manner to be presently described, the descent of the ram occurring when the liquid is allowed to escape through the pipe J. The ram is secured to the arm D at d. The high pressure liquid is by the pipe I conducted to the space between the two pistons of a double piston-valve K¹ K² which fits the valve casing L. When the double piston-valve has been displaced downward from the position shown in Fig. 2 the pipe I will be placed in communication with the bore of the ram H and liquid under pressure will be able to enter the cylinder G and force the ram H and carbon electrode C upward whereas if K¹ K² is displaced upward, the liquid in the cylinder G will be able to escape to the pipe J and permit the ram H and electrode C to descend toward the molten metal B in the furnace A.

The high pressure liquid in the space between K¹ K² will tend to lift K¹ K² by virtue of the larger area of the piston K¹. This tendency will be counteracted by the provision of a bore hole k¹ through the piston K¹ which will permit the liquid to leak to the space above K¹ and press on the upper side thereof. The displacement of the double piston-valve K¹ K² will be further affected by the provision of a central leakage passage leading from the space above K¹ to the escape pipe J. This passage is commanded by an

escape valve K which is an entirely balanced valve controlled in its operation by an electro-magnetic device to be presently described.

5 In one form of the electro-magnetic device, shown in Fig. 2, I provide two electro-magnets M¹ M², M¹ being secured to a prolongation of the spindle of the above mentioned escape-valve K which prolongation 10 serves as a solenoid core for the fixed electro-magnet M².

N is the main electric lead to the carbon electrode. From this a shunt line O is taken to a rheostat P and from this the shunt current 15 is caused to traverse the windings of the electro-magnets M² M¹ and rejoin the main lead N by the lead O¹ as shown.

The potential in N at the point from 20 which the shunt line O is taken is sufficiently greater than that at which the shunt current rejoins the main current by the lead O¹ to appropriately energize the electro-magnets M² M¹.

When the current is passing, the magnet 25 M¹ will be attracted toward the fixed magnet M² and tend to close the escape valve K against the compressive force of a spring Q which tends to keep the valve open.

When the current in the main electric lead 30 N, and consequently in the shunt O therefrom, has become unduly small on account of the electrode C being insufficiently immersed in the furnace metal B, the spring Q will overpower the pull of the magnet M¹ 35 and raise the escape valve K thus relieving the pressure in the space above K¹. The pressure of the liquid in the supply pipe I will then raise the double piston-valve K¹ K² and permit some of the liquid in the cylinder 40 G to escape and the ram and carbon electrode to descend and increase the immersion of the latter in the metal B. The raising of K¹ K² will lessen the area of escape past the valve K. At the same time the augmentation 45 of the electric current by the increase of the immersion of the electrode in the metal in the furnace will increase the attraction of the magnet M¹.

Thus a very small displacement will cause 50 a correct automatic regulation of the electric current by the interaction of the ram H, the valve K, the piston-valve K¹ K² and the electro-magnet M¹.

By the use of the rheostat P a hand adjustment 55 of the current may be superposed on the automatic adjustment and enable the contrivance to be employed under a variety of conditions.

By reference to Fig. 3 an alternative construction 60 of electro-magnetic adjusting device will be described. In this design, instead of the energizing electric current being a shunt from the main electric lead to the carbon electrode as in the arrangements 65 shown in Fig. 2, I may employ a transformer

indicated at R in Fig. 3 to generate a secondary electric current in the wire S, N, as before, indicating the main electric lead to the carbon electrode which is employed by the primary current. The secondary current 70 is used to energize an electro-magnetic device which comprises a construction T such as is employed in a single-phase repulsion motor. The rotor element of T is constrained by a spring U which reverses the 75 rotor when the electric current is relaxed. To the rotor a cam V of gradually increasing radius is secured, whereby a roller-terminated lever W is employed to operate the previously described escape-valve K and 80 open it against the compressive force of the spring Q.

The secondary current from the wire S will develop a torque between the rotor and stator elements of the repulsion motor T 85 which will be practically uniform for all angular positions of the rotor. Inasmuch as the torque will increase and decrease with the current, the rotor and cam V will take angular positions corresponding to the 90 fluctuating electric current through N and S and correspondingly regulate the positions of the valvular elements K, K¹ K².

I claim:

1. An apparatus for maintaining a constant current through an electric furnace comprising fluid pressure means for modifying the position of the furnace electrode, valvular elements for regulating the supply of fluid to said means, electro-magnetic 95 means controlling said valvular elements, and a source of current having a circuit including said electro-magnetic means and the furnace electrode in a manner to effect an automatic adjustment of said valvular elements by said electro-magnetic means.

2. An apparatus for maintaining a constant current through an electric furnace comprising fluid pressure means for modifying the position of the furnace electrode, 110 valvular elements for controlling the supply of fluid to said fluid pressure means and actuated by the fluid, a source of current, a circuit including said source of current and the furnace electrode, and an electro-responsive device included in said circuit in such manner that the supply of current thereto is in accordance with the position of the furnace electrode, whereby the position of the valvular elements would be automatically 120 adjusted.

3. An apparatus as described in claim 1, and a balance escape valve actuated by said electro-magnetic means for controlling the movements of the valvular elements.

4. An apparatus for maintaining a constant current through an electric furnace comprising fluid-pressure means for modifying the position of the furnace electrode, 125 valvular elements actuated by the fluid-pres- 130

sure means for regulating the supply of fluid to said fluid-pressure means, a balance escape valve for controlling the passage of fluid to said valvular elements, a source of current, a transformer, an electro-responsive device energized by said transformer and biased to a predetermined position, and a circuit including said source of current, said transformer, said furnace electrode, and said electro-magnetic means in such manner that an automatic adjustment of the escape valve by means of said electro-magnetic means is effected.

5. An apparatus as described in claim 4, and a rheostat included in said circuit for controlling the supply of current through said electro-magnetic means.

6. In combination, an electric furnace including an electrode, means for adjusting the position of said electrode, fluid-pressure means for actuating said means, valves for controlling said fluid-pressure means and biased to a predetermined position, cam-actuated means for moving said valves against their bias, electro-magnetic means for con-

trolling said cam-actuated means, and a source of current having a circuit including said electro-magnetic means and the furnace electrode.

7. In combination, an electric furnace including an electrode, fluid-pressure means for adjusting the position of said electrode, valves for controlling the fluid-pressure means and biased to a predetermined position, an escape valve for controlling the movement of said valves, electro-magnetic means for controlling said escape valve comprising a solenoid and an electro-magnet, a source of current having a circuit including said electro-magnetic means and the furnace electrode, and means for manually controlling said electro-magnetic means.

8. In testimony whereof I have signed my name to this specification in the presence of two subscribing witnesses.

JENS ORTEN BOVING.
